Letter Patent

The Schedule referred to in these Letters Patent, and making part of the same, containing a description in the words of the said Charles Davenport, himself, of his improvement in Rail Road Cars by means of Springs for easing the motion or shock produced at the moment of Stopping or Starting.

Be it known where these presents shall come, Be it known that I Charles Davenport of Cambridge in the County of Middlesex and State of Massachusetts have invented a new and useful improvement in Rail road Cars by means of Springs for easing the motion or shock produced at the moment of Stopping or of Starting, and that the following is a full and exact description of the construction and operation of the said machine as invented or improved by me.

My improvement is to be applied by connecting the cars, in such a manner as to ease the first shock of starting or rest, it is to be between each couple, by being secured to the middle piece running through the frame of the carriage, or what is commonly termed the pack in coaches. The manner of constructing these Springs and their auxiliary fixtures, I content in the following manner. At about two and a half feet from the end of the middle piece and on the top thereof I mean except it is in the direction of the width of the frame, to connect some circular Springs as then known as elliptical cars by means of two pieces of plank of all time, makes high, be them firmly on the middle piece one at each side. The Springs are let into these pieces as low down as to be about flush with the top and then secured by means of a stop bolted up, and the opening is to be sufficiently large to admit the full play of the Springs.

They are an inch diameter, & consist of as many turns as may be requisite for the strength, and strength. The centre of each one opening is to be made, to admit a rod of about six inches in length, through the thickness of leaves, & which is to be riveted or otherwise secured on the inside so that the rod projects entirely from the outside of each elliptical half and middle piece. A long flat bar is placed beneath these Springs to rest and slide back and

and forward upon the middle piece and directly beneath them upon the top of the springs is also laid along another flat piece of sufficient length to embrace the whole distance of expansion of these, and also to allow its ends to be bent down the width of them, and then to be secured to the bar below them forming a square loop extending the entire of them. A hole is to be made through each bar end of this loop, directly opposite to the rod, and which is intended to play easily either backwards or forwards on this rod which is passed through it for that purpose.

The other end of the flat bar projects beyond the carriage frame as far as may be necessary & has a pin or hook or other contrivance by which the connection with the other car is to be effected. In the operation of these springs the shock which for example would suppose to be that of starting causes the end of the bar furnished with the hook or pins for connection to be drawn out in the foremost car. This of course draws back the square loop with it, causing it to press against the outside of the front semicircle and being brought back also at the same time the back or hinder spring, pressing against the opening in the plank cannot recede, but the loop passes on along the rod by means of the opening left for that purpose and which rods must be equal in length to the play of the springs say abt six inches so that the hole in the loop cannot pass over the ends of either rod. The reverse mode of operation will attend the other shock or that of stopping. A single or square loop is also to pass over the connecting end of the bar so as to retain it in its proper position on the middle piece. These springs may be used to every car & only alternately.

The same effect may be produced by using spiral instead of the elliptical springs, and in this case the opening in the side pieces is made much longer, so as to admit a long spiral spring to be horizontally turned having a sufficient bend in the coil to receive a rod as long as the opening which keeps the coil straight. As many of these spring coils may be used upright or upright but in general three will answer well one at each side and one in the middle. The long flat bar is the same below the square loop but which must be as long as the opening or length of the springs. Through the hole in the middle is secured a rod by welding, otherwise for the central spiral to connect one of the same length as the others. A short flat bar is to pass across the end of the square loop one at each end or from one side of the springs on the planks of the other

These bars have each as many holes in, as rods or springs are used, & these have play by means of these holes, up & down the rods. The remaining fixtures are the same in both cases. In the operation of this plan, the shock produced by starting will draw back the flat bar and trigger loop, and with it also the forward flat bar, which at each end slides down the rod and contacts the spring which is resisted at the other end but the middle rod being fast to the loop is drawn back and passes through the hole through the short bar at the opposite end thereby contracting its spring also.

What I claim as my invention in the above described machine and not before used is the application of the one spring acting both ways in either ends the contraction and contraction made use of to provide against either shock in starting or stopping, by the action of the springs either from front or from behind. Testimony that the above is a full and exact description of the construction and operation of my machine as invented or improved by me. I have hereunto set my hand this thirty first day of July eighteen hundred and and thirty six.
